UNITED STATES PATENT OFFICE.

EDGAR M. HAWKINS, OF ROCHESTER, NEW YORK, ASSIGNOR TO M. D. KNOWLTON COMPANY, OF ROCHESTER, NEW YORK, A CORPORATION OF NEW YORK.

SAFETY OPERATING MECHANISM.

1,138,025.

Specification of Letters Patent. Patented Mar. 23, 1915.

Application filed July 15, 1914. Serial No. 851,069.

To all whom it may concern:

Be it known that I, EDGAR M. HAWKINS, citizen of the United States, and resident of Rochester, in the county of Monroe and State of New York, have invented certain new and useful Improvements in Safety Operating Mechanism, of which the following is a specification.

This invention relates to operating mechanism for punching machines, presses, box-staying machines and the like, and has for its object to provide a novel safety operating mechanism of such character as to render the work-performing element of the machine effective only when it is proper that the same should be effective. In other words, if an obstruction, such as the operator's hand or any other part of his body, lies in the path of the work-performing element, the operating mechanism will not impart an effective working stroke to the work-performing element. The operator's safety is thus assured, as there is no danger of injury from the work-performing parts.

In furtherance of this object, the invention consists in providing a collapsible link or pitman between the work-performing element of the machine and the actuating means therefor. The collapsible link or pitman consists of two relatively movable members which are normally adapted to telescope or move relative to each other when an obstruction, other than the work to be operated upon, lies in the path of the work-performing element. Means is provided, however, for rendering the parts of the pitman rigid just prior to the engagement of the work by the work-performing element on each stroke, and if no obstruction is encountered, the work is, therefore, properly acted upon. This means preferably takes the form of an element which is shifted during the movement of the pitman to positively connect the relatively movable parts of the pitman and thereby render said parts rigid and non-collapsible.

The invention further consists in providing means for protecting said shiftable element against accidental movement and thereby preventing shifting of the same until the proper time.

The invention also consists in certain other novel features, which will hereinafter be described.

The invention is illustrated in the accompanying drawings, in which:—

Figure 1 is a front elevation of the collapsible pitman or link, and certain parts adapted to coöperate therewith; Fig. 2 is a side elevation of the construction shown in Fig. 1; Fig. 3 is a front elevation of a box-staying machine showing the collapsible pitman applied thereto; Fig. 4 is a side elevation of the construction shown in Fig. 3; Fig. 5 is a sectional view taken on the line 5—5 of Fig. 2; Fig. 6 is a sectional view taken on the line 6—6 of Fig. 5; Fig. 7 is a sectional view taken on the line 7—7 of Fig. 6; and Fig. 8 is a vertical section taken on line 8—8 of Fig. 7.

Similar reference characters indicate like parts in the several figures of the drawings.

The collapsible pitman or link, hereinbefore referred to, comprises two relatively movable parts A and B. The part A is adapted to telescope within the part B, but is normally retained in the position shown in the drawings by means of the longitudinally slidable plugs 1, mounted in cylindrical openings or bores formed in the outer member B. The inner ends of the plugs 1 are provided with the projections 2 presenting an inclined cam face 3 at their upper surface, and a horizontally disposed check face or stop face 4 at their under surface. These projections 2 are adapted to engage in correspondingly formed recesses 5, (Fig. 6), formed in the inner member A. The slideable plugs 1 are spring-pressed and are held in the position shown in Fig. 1, preferably by means of the leaf-springs 6 secured to the side portions of the outer member B, and engaging at their upper extremities, the slideable plugs 1. The upper extremities of the springs 6 are slotted, as shown at 7, to engage projecting portions 8 on the slideable plugs 1. The plugs 1 are therefore spring-pressed toward the member A, and the strength of the springs 6 is such that the parts will normally retain the position shown in Fig. 1. In other words, if the part B, or any part which it operates, meets with no obstruction during its movement, the part A will actuate the part B in the same manner as if the two were rigidly connected. If the movement of the part B is resisted, however, the part A, in descending, will act upon the cam faces 3 of the

plugs 1, thereby forcing the plugs outwardly and permitting the parts A and B to telescope or to move relatively to each other, due to the fact that the part A will further descend without moving the part B.

Pivots associated with the lower part B of the collapsible link is a pivoted dog 9 for connecting the relatively movable parts A and B when the work-performing element 10 nears the end of its working stroke. This dog 9 consists of a vertically disposed arm 9', and a horizontally disposed arm 9''. The normal position of the dog 9 is that shown in Fig. 2, in which the vertically disposed arm 9' is in alignment with a recessed or cut-out portion 10, formed at the lower extremity of the upper member A of the link or pitman. The horizontal portion 9'' of the dog 9 rests upon a lever 11 pivotally connected to the part B at 12, (Fig. 1), and positioned transversely of the part B, as best shown in Figs. 1, 5 and 7. The outer or free end of the lever 11 is supported by a pin 13 set in the inner face of the member 15 B. The dog 9, therefore, normally has no effect in preventing the collapsing or telescoping movement of the parts A and B, above described.

The pitman constructed as described above, may be applied to many different kinds of machines, such as punches, presses, box-staying machines and the like. In Figs. 3 and 4, the pitman is shown associated with a box-staying machine, in which the upper member A of the pitman is eccentrically connected with the driving shaft C of the machine and the lower member B is connected to the sliding head D, which carries at its lower part the movable die or jamb E 40 of the staying machine.

Besides the pitman structure hereinbefore described, the safety operating mechanism comprises certain fixed parts, which are preferably carried by an auxiliary or independent supporting bracket F, which may be secured to any suitable fixed part of the machine to which the pitman is applied. In the present instance, the bracket F is attached to that part of the frame which carries the stationary die or anvil G with which the movable die E cooperates in applying a stay to a box corner. Said bracket is provided with an upright portion 14 having a longitudinal recess or opening 15 to accommodate a longitudinally slidable bolt 16. This bolt 16 is preferably a T-bolt, having at its lower extremity a cross-piece 17 which supports a casting 18, associated with the lower part of the upright portion 14 of the frame F. A spring 19, positioned in the opening 15, serves to retain the T-bolt in the position shown in Fig. 8. The part 18 is held in proper relation with respect to the part 14 by means of a dowel-pin 20, set in the part 14 and loosely engaging in an open-

ing 21 of the part 18, whereby said part 18 is permitted to move relative to the part 14, during which movement, the T-bolt will be lowered and the spring 19 compressed.

The part 18 is provided with a projection 22, which lies in the path of the lever 11 and is so positioned, that the lever 11 will contact with the projection 22 just prior to the engagement of the work-performing element E with the work. In practice, it has been found desirable to so position the parts that the projection 22 will act on the lever 11 when the work-performing element E is about one-eighth of an inch from the work to be operated upon. When the lever 11 thus contacts with the projection 22, the dog 9 is swung to the left in Fig. 2, thereby bringing the vertically disposed portion 9' directly under a shoulder 23 formed at the lower extremity of the part A. A rigid connection will therefore be established between the parts B and the part A, and the pitman will be rendered effective for transmitting the proper amount of power to the work-performing element to enable it to properly perform its function. In order that the projection 22 will not interfere with the completion of the stroke of the pitman after the lever 11 contacts with the projection, the projection 22 and the part 18 with which it is associated, moves downwardly and compresses the spring 19 in the manner above described. The part 18, therefore, yields after the dog 9 is thrown under the shoulder 23, but the strength of the spring 19 is such as to cause the dog to be so actuated before the part 18 will yield.

In order to prevent accidental displacement of the dog 9 before it is actuated by the projection 22, a protecting element 24 is provided, a projection 25 of which normally overlies the horizontal portion 9'' of the dog 9. The protecting element 24 is pivotally connected with the part B at 26, and is held in the position shown in Fig. 2 during the greater part of the movement of the pitman by means of a roller 27 carried by the upright part 14 of the frame F. Just prior to the engagement of the projection 22 by the lever 11, a cam surface 28, formed on the part 18, co-acts with the lower extremity 29 of the protecting element 24, and thereby swings the same to the right in Fig. 2, and releases the horizontal portion 9'' of the dog 9. At this stage of the operation, the inclined portion 30 of the protecting element 24 is adjacent the roller 27 whereby is permitted the swinging movement of the protecting element 24, just described. After the protecting element 24 is deflected by the cam surface 28, the dog 9 may be swung under the shoulder 23 by the lever 11 and projection 22, as hereinbefore described. On the up stroke of the pitman, the roller 27 cooperates with the inclined part 130

30 of the protecting element 24, and swings the same back to the position shown in Fig. 2, during which swinging movement, a cam surface 31, provided on the projection 25, 5 engages with a corresponding cam surface 32 on the dog 9 to return the dog to the position shown in Fig. 2. In order to make certain that the dog 9 assumes such a position that the shoulder 23 will not contact 10 with the portion 9' of the dog at the beginning of the stroke of the pitman, a projection 33 is provided (see Figs. 5 and 6) with which the horizontal portion 9'' of the dog contacts at the completion of the upstroke 15 of the pitman to swing the dog to the position shown in Figs. 2 and 6, in case the same is not already in such position.

It is obvious that if the work-performing element of the machine meets with an obstruction, such as the operator's hand or any 20 part of his body, before the dog 9 is thrown under the shoulder 23, the pitman will collapse, or, in other words, the part A will complete its stroke without carrying with it 25 the portion B. The parts B and A, therefore, constitute yielding connections, which will normally yield when the work-performing element meets with an obstruction, but which are rigidly connected just prior to 30 the engagement of the work by the work-performing element. If the operator's hand lies in the path of the work-performing element, it will, therefore, be uninjured, due to the fact that when the work-performing 35 element contacts with the operator's hand, the parts will not have been rigidly connected, and the part B will, therefore, yield. If the work-performing element meets with no obstruction, the part B will be rigidly 40 connected with the part A when the work-performing element is about one-eighth of an inch from the work, by means of the dog 9, the vertical portion 9' of which is swung under the shoulder 23 by the lever 11 and 45 projection 22, as above described. The connections are, therefore, made rigid and the pitman is then capable of transmitting the required power to the work-performing element to accomplish its purpose. On the up 50 stroke of the pitman, the dog 9 will be shifted to the position shown in Figs. 2 and 6 to render the connections yieldable in case that an obstruction is met with on the following down stroke of the pitman. If an 55 obstruction is encountered and the parts A and B telescope or yield, the part B will be held substantially stationary by the obstruction, but the part A will complete its stroke and will again be connected with the part B 60 during its up stroke, as the projections 2 of the slideable plugs 1 will reengage with the recesses 5 in the part A, and the horizontally disposed surfaces 4 of said projections will cause the part A to "pick up" the part B, 65 which will, therefore, again be restored and

normally retained in its proper relation with respect to the part A.

What I claim is:—

1. Safety operating mechanism for machines of the kind described, comprising a pitman having relatively movable and yieldable parts, a pivoted element mounted in the interior of one of said parts, and means automatically operative near the end of the stroke of the pitman to shift said element to render said parts rigid and non-yieldable for the remainder of the stroke. 75

2. Safety operating mechanism for machines of the kind described, comprising a pitman having relatively movable and yieldable parts, a pivoted dog mounted in the interior of one of said parts, and means automatically operative near the end of the stroke of the pitman to shift said dog to render said parts rigid and non-yieldable for the remainder of the stroke. 85

3. In a machine of the kind described, the combination with the actuating means and the work-performing means, of normally yieldable connections between the same comprising relatively movable parts, a pivoted bell-crank lever associated with said parts and adapted to serve as a direct connection between the same, and means operative just prior to the engagement of the work by the work-performing means and operable directly on one arm of the bell-crank lever to shift the same to render said connections rigid and non-yieldable until after the work is operated upon. 90

4. Safety operating mechanism for machines of the kind described, comprising a pitman having relatively movable and yieldable parts, a pivoted element mounted in the interior of one of said parts, and yielding means automatically operative near the end of the stroke of the pitman to shift said element to render said parts rigid and non-yieldable for the remainder of the stroke. 105

5. Safety operating mechanism for machines of the kind described, comprising a pitman having relatively movable and yielding parts, a pivoted dog carried by one of said parts, the other part having a recess adapted to accommodate a portion of the dog if the parts are moved relative to each other, and means operative near the end of the stroke of the pitman to shift the position of the dog out of alignment with said recess to prevent relative movement of said parts. 115

6. Safety operating mechanism for machines of the kind described, comprising a pitman having relatively movable parts, one of said parts having a spring-pressed plug, the inner extremity of said plug having an inclined surface at one side thereof and a locking surface at the other side thereof, the other part of the pitman hav- 120

- ing a corresponding recess to receive said plug extremity to yieldingly resist relative movement of said parts in one direction and to lock said parts against relative movement in the opposite direction, and means automatically operative near the end of the stroke of the pitman to render the parts thereof rigid and non-yieldable. 5
7. Safety operating mechanism for machines of the kind described, comprising a pitman having relatively movable and yielding parts, a movable element carried by one of said parts, means automatically operative near the end of the stroke of the pitman to shift said element to render said parts rigid and non-yieldable for the remainder of the stroke, and means to prevent accidental shifting of said element before said last-named means operates. 10
8. Safety operating mechanism for machines of the kind described, comprising a pitman having relatively movable and yielding parts, a pivoted dog carried by one of said parts, means automatically operative near the end of the stroke of the pitman to shift said dog to render said parts rigid and non-yieldable for the remainder of the stroke, and means to prevent accidental shifting of said dog before said last-named means operates. 15
9. Safety operating mechanism for machines of the kind described, comprising a pitman having relatively movable and yielding parts, a movable element carried by one of said parts, means automatically operative near the end of the stroke of the pitman to shift said element to render said parts rigid and non-yieldable for the remainder of the stroke, protecting means to prevent accidental shifting of said element before said last-named means operates. 20
10. Safety operating mechanism for machines of the kind described, comprising a pitman having relatively movable and yielding parts, a pivoted dog carried by one of said parts, means automatically operative near the end of the stroke of the pitman to shift said dog to render said parts rigid and non-yieldable for the remainder of the stroke, protecting means to prevent accidental shifting of said dog before said last-named means operates, and automatic means to shift said protecting means to inoperative position to permit the element to be shifted by said means. 25
11. Safety operating mechanism for machines of the kind described, comprising a pitman having relatively movable and yielding parts, a movable element carried by one of said parts, means automatically operative near the end of the stroke of the pitman to shift said element to render said parts rigid and non-yieldable for the remainder of the stroke, protecting means to prevent accidental shifting of said element before said last-named means operates, and automatic means to shift said protecting means to inoperative position to permit the dog to be shifted by said means. 30
12. Safety operating mechanism for machines of the kind described, comprising a pitman having relatively movable and yielding parts, a pivoted dog carried by one of said parts, means automatically operative near the end of the stroke of the pitman to shift said dog to render said parts rigid and non-yieldable for the remainder of the stroke, protecting means to prevent accidental shifting of said dog before said last-named means operates, means to prevent shifting of said protecting means throughout the greater part of the stroke of the pitman, and automatic means to shift said protecting means to inoperative position to permit the element to be shifted by its shifting means. 35
13. Safety operating mechanism for machines of the kind described, comprising a pitman having relatively movable and yielding parts, a movable element carried by one of said parts, means automatically operative near the end of the stroke of the pitman to shift said element to render said parts rigid and non-yieldable for the remainder of the stroke, and means carried by the pitman to prevent accidental shifting of said element before said last-named means operates. 40
14. Safety operating mechanism for machines of the kind described, comprising a pitman having relatively movable and yielding parts, a movable element carried by one of said parts, means automatically operative near the end of the stroke of the pitman to shift said element to render said parts rigid and non-yieldable for the remainder of the stroke, protecting means carried by the pitman to prevent accidental shifting of said element before said last-named means operates, and automatic means to shift said protecting means to inoperative position to permit the element to be shifted by said means. 45
15. Safety operating mechanism for machines of the kind described, comprising a pitman having relatively movable and yielding parts, a pivoted dog carried by one of said parts, means automatically operative near the end of the stroke of the pitman to shift said dog to render said parts rigid and non-yieldable for the remainder of the stroke, protecting means carried by the pitman to prevent accidental shifting of said dog before said last-named means operates, and automatic means to shift said protecting means to inoperative position to permit the dog to be shifted by said means. 50

- ing means to inoperative position to permit the dog to be shifted by said means.
16. Safety operating mechanism for machines of the kind described, comprising a pitman having relatively movable and yielding parts, a pivoted dog carried by one of said parts, means automatically operative near the end of the stroke of the pitman to shift said dog to render said parts rigid and non-yieldable for the remainder of the stroke, pivoted protecting means carried by the pitman to prevent accidental shifting of said
- dog before said last named means operates, and automatic means to shift said protecting means to inoperative position to permit the dog to be shifted by said means.
- Signed at Rochester, in the county of Monroe and State of New York, this 13 day of July A. D. 1914.
